UNITED STATES PATENT OFFICE.

FLOYD PHILP, OF LOMPOC, CALIFORNIA.

DRAFTSMAN'S POUNCE BLOCK.

Application filed September 30, 1924. Serial No. 740,883.

To all whom it may concern:

Be it known that I, FLOYD PHILP, a citizen of the United States, and a resident of Lompoc, in the county of Santa Barbara 5 and State of California, have invented a new and useful Draftsman's Pounce Block, of which the following is a specification.

This invention relates to means for preparing the surfaces of drawing or tracing cloth before working thereon and has for its object an improved pounce block to simplify such preparation of the cloth and to do away with the dustiness and flying about 10 of the pounce powders heretofore used for 15 the purpose mentioned.

The drawings hereto show two modifications of my invention, the figures being substantially full size perspective views of the two forms.

20 In Figure 1 the simplest embodiment of the invention is shown and consisting of a block 1 of substantially pure silica (diatomaceous earth) to which a piece of felt 2 or other soft fibrous material is attached by 25 glue, cement, varnish, or other adhesive.

In the form shown in Figure 2 the elements described are the same plus a block of wood 3 glued to the felt and another piece of felt 2' glued to the outer surface 30 of the wood.

In this latter construction, the wood is preferably grooved around the exposed edge as shown at 4 to afford a finger grip-

ping channel, and it should be noted that the felt 2' acts as a bed for the glue so it 35 will get a good grip on both the wood and block, therefore, can be extremely thin, or may be a sheet of heavy paper.

The blocks both function alike, the diatomaceous block being first rubbed over the 40 parts of the cloth to be inked upon, then the block turned over to bring the felt against the cloth and the slight amount of powder which was deposited from the block 45 is well rubbed into the cloth in the usual way.

I claim.

1. A pouncing device for tracing cloth and other drawing surfaces comprising a block of pounce material having a strip of 50 fibrous material secured thereto.

2. A pouncing device for tracing cloth and other drawing surfaces comprising a block of pounce material having a strip of 55 felt secured to one side thereof.

3. A pouncing device for draftsman's tracing cloth consisting of a block of pouncing material formed with a flat surface adapted for rubbing on the tracing cloth surface, a piece of fibrous material stuck to the opposite surface, a gripping block stuck to the fibrous material, and a sheet of fibrous material secured over the outer surface of the gripping block.

FLOYD PHILP.
